MAILING CARTON FOR BOOKS

Application filed February 4, 1930. Serial No. 425,737.

My invention relates to mailing cartons.

The object of my invention is to provide a mailing carton for books that may be made at a low cost, permit of quick inspection of its contents by postal authorities, and which is held in closed condition by a metal locking device in place of cord or binding tape, as now generally used.

Referring to the drawings which form a part of this specification:

Fig. 1 is a perspective view of a carton shown partly in section, and in a partly open condition.

Fig. 2 is a perspective view of a carton in its closed and locked condition, and shown partly in section to disclose a book therein.

10— indicates the outer casing of a carton made of stiff thick card-board or other suitable material and formed with open ends 20—11— in the usual manner.

12— indicates the wrapper portion of the casing which includes the ends —13—.

The inner portion —12— may be removed from the casing thru either end thereof, and 25 a book —14— slipped in from either open side thereof in the usual manner, after which the inner portion is inserted in the casing as illustrated in Figure 2.

My improvement in this type of carton 30 consists in forming an opening —15— shaped substantially circular with a notch or recess —16— at one side as illustrated, and using a clip to lock the parts together, instead of tape or cord.

35 The locking means comprise a clip —17— made of tough soft metal, such as sheet iron or brass, and having a shank portion —18— with prongs of the usual construction formed integral and extending thru the card-board 40 —12— and clinched in the under side thereof to hold the clip firmly in position thereon.

The opening —15— is made of sufficiently greater diameter than the diameter of the head portion —19— to permit said head portion to be reached and lifted by a finger in

the locking operation, the clip being bent over into the position shown to lock the parts together, with the neck portion resting in the recess —20— to prevent shifting of the wrapper portion endwise in the casing. 50

In forming the clip the head portion —19— is pressed into a partly spherical shape to stiffen it, and the neck portion —20— is reduced in width to permit the clip to be easily bent at this point, in the act of 55 locking the carton.

By locating the clip midway between the ends of the casing, and near one side thereof as illustrated, the middle portion is left clear for the usual address label —21—. 60

By making the width of the recess to correspond with the width of the neck portion —20— all end movement of the part —12— is prevented.

Constructed as above described, the carton 65 may be quickly filled and locked, ready for shipment, and may be inspected without unnecessary loss of time.

Having thus described my invention, I claim as new:

1. In a mailing carton of the character described, a casing of rectangular form open at each end, a wrapper portion including a side and hinged ends cooperating with the casing to provide end closures for said casing, 75 and an interlocking connection between the casing and wrapper located substantially midway the ends of the wrapper side adjacent a side edge thereof to permit removal of the wrapper from either end of the casing and 80 presenting uninterrupted address areas on both sides of the casing.

2. In a mailing carton of the character described, a casing of rectangular form open at each end, a wrapper portion including a 85 side and hinged ends cooperating with the casing to provide end closures for said casing, and an interlocking connection between the casing and wrapper located substantially midway the ends of the wrapper 90

side adjacent a side edge thereof to permit removal of the wrapper from either end of the casing and presenting uninterrupted address areas on both sides of the casing, the 5 interlocking connection between the casing and wrapper including the provision of an opening in the casing and a metallic clip carried by the wrapper adapted to be projected through the opening and bent to over-
10 lie a portion of the casing.

In testimony whereof I have affixed my signature.

HERMAN L. GREVE.
